UNITED STATES PATENT OFFICE.

HARVEY F. CRAWFORD AND RICHARD C. LAMBERT, OF BROCKTON, MASSACHUSETTS; SAID LAMBERT ASSIGNOR OF ONE-THIRD OF HIS INTEREST TO SAID CRAWFORD.

MECHANISM FOR PROPELLING VEHICLES.

SPECIFICATION forming part of Letters Patent No. 444,130, dated January 6, 1891.

Application filed June 23, 1890. Serial No. 356,316. (No model.)

To all whom it may concern:

Be it known that we, HARVEY F. CRAWFORD and RICHARD C. LAMBERT, of Brockton, county of Plymouth, State of Massachusetts, have 5 invented an Improvement in Vehicles and Means for Propelling the Same, of which the following description, in connection with the accompanying drawings, is a specification, like letters and figures on the drawings representing like parts.

This invention has for its object to provide a novel vehicle and means for propelling the same, whereby greater power may be exerted by the operator.

15 In accordance with this invention the axle carrying the drive-wheels has formed upon it a crank which is turned by two pitmen connected to and driven by suitable pistons which are reciprocated in hydraulic cylinders, 20 the water or other liquid being forced into the cylinders behind the pistons by plungers of small diameter actuated by a lever preferably operated by hand.

One part of our invention therefore consists 25 in the frame and the drive-axle having bearings therein and provided with a crank, combined with a cylinder having a piston to operate the said crank, a plunger for said cylinder, and mechanism to operate said plunger, 30 substantially as will be described.

Our invention also consists in certain novel features of construction embodied in the vehicle itself, to be hereinafter described, and pointed out in the claims.

35 Figure 1 shows in side elevation and partial section a vehicle embodying this invention; Fig. 2, a top or plan view of the same; Fig. 3, a vertical section taken on the dotted line $x-x$, Fig. 1; and Fig. 4, an enlarged detail to be referred to.

Referring to the drawings, the frame A, of 45 suitable shape, has bearings for the main drive shaft or axle a , on which are mounted at each end the drive-wheels b . The drive shaft a at its middle has formed in it the crank a' , driven by the oppositely-extended pitmen $a^2 a^3$, connected at their outer ends to the pistons a^4 , fitted to move in the cylinders $a^5 a^6$, supported in suitable manner by the frame 50 at opposite sides of the axle, as shown. To

the opposite outer sides of the cylinders $a^5 a^6$ are connected pipes or tubes a^7 , preferably curved over above to face each other, as shown, to receive the plungers a^8 at opposite ends of the reciprocating bar a^9 , shown as 55 provided with a stud or pin a^{10} , which works in a vertical slot a^{11} in the operating-lever a^{12} , shaped, as shown, to clear the axle a , and pivoted at its lower end at a^{13} between the two stays or braces a^{14} , depending from and secured to the frame, the said lever at its upper end being provided with a suitable handle a^{15} .

The pipes a^7 , in which the plungers a^8 work, are supported by brace-rods a^{16} , carried by the frame. The pipes a^7 are filled with water 65 or other liquid through suitable openings at 15 provided for that purpose, so that when the bar a^9 , carrying the plungers a^8 , is reciprocated by the operating-lever the water will be forced alternately into the cylinders $a^5 a^6$ 70 behind their pistons to reciprocate them, and, acting through the pitmen a^2 , will turn the crank a' and rotate the axle a to move the vehicle.

The frame A at opposite ends is provided 75 with suitable sockets which receive the rotatable spindles $b' b^2$, formed at their lower ends to receive and carry the wheels $b^3 b^4$, one of the spindles, as b' , being surrounded by a spiral spring 25, interposed between a shoulder on the said spindle and the end of the socket, in which it enters to allow the vehicle to yield to any irregularities in the road. The axles or journals of said wheels $b^3 b^4$ are extended out longitudinally and have swiveled 85 to their outer ends the steering-rods $b^5 b^6$, jointed at their inner ends to the ends of the bar b^7 , fast on the lower end of the vertical shaft b^8 , mounted in suitable supporting rods b^9 , carried by the frame, the said shaft at its 90 upper end being provided with a cross-bar b^{10} , carrying adjustably the foot-rests or sockets b^{11} .

A seat s is supported, as shown, above the frame.

When the vehicle is in use, the operator is seated upon the seat s , with his feet upon the rests b^{11} , the lever a^{13} being moved back and forth by the arms to reciprocate the plungers a^8 and thereby operate the pistons a^4 to turn 100

the axle. The wheels b^3 b^4 are turned in one or another direction to guide the vehicle by turning the rests b^{11} with the feet, as will be seen by reference to Figs. 2 and 4 of the drawings.

We do not desire to limit our invention to the particular form and construction herein represented, as the same may be varied without departing from the scope of this invention.

It will be seen that the propelling mechanism is adapted, with slight modifications, to any other form of vehicle as well as the one shown, the power exerted upon the crank being greatly increased thereby.

We claim—

1. The frame and the drive-axle having bearings therein and provided with a crank, combined with two cylinders having pistons to operate the said crank, plungers for said cylinders placed substantially in line, and mechanism to reciprocate the said plungers in unison, substantially as described.

2. The frame A and the drive-axle having

bearings therein and provided with a crank, combined with a cylinder having a piston, a pitman connecting said piston and crank, a plunger for said cylinder, and a lever to operate said plunger, substantially as described.

3. The frame A and drive-axle a , having bearings in said frame and provided with a crank, combined with the cylinders a^5 a^6 , pistons a^4 , pitmen a^2 a^3 , plungers a^8 , and the pivoted lever a^{12} to operate plunger, substantially as described.

4. The frame A, the drive-axle having bearings therein, and the wheels b , combined with the wheels b^3 b^4 , rods b^5 b^6 , bar b^7 , shaft b^8 , and cross-bar b^{10} , to operate substantially as described.

In testimony whereof we have signed our names to this specification in the presence of two subscribing witnesses.

HARVEY F. CRAWFORD.
RICHARD C. LAMBERT.
